BURT T. ROGERS, OF SPRINGFIELD, MASSACHUSETTS, ASSIGNOR TO VICTOR SPORTING GOODS COMPANY, OF SPRINGFIELD, MASSACHUSETTS, A CORPORATION.

BASE-BALL MITT OR GLOVE.

1,018,271.

Specification of Letters Patent.

Patented Feb. 20, 1912.

Application filed October 29, 1908. Serial No. 460,054.

To all whom it may concern:

Be it known that I, BURT T. ROGERS, a citizen of the United States of America, residing at Springfield, in the county of Hampden and State of Massachusetts, have invented new and useful Improvements in Base-Ball Mitts or Gloves, of which the following is a specification.

This invention relates to the construction 10 of a combined glove and mitt such as is used by players of the game of base-ball.

Heretofore it has been customary to manufacture a mitt, so called, which is used especially by a player occupying certain positions in the game and a glove which is used by players occupying certain other positions.

There are many reasons why it is desirable to use a protective covering for the hand of the player which will possess the 20 qualities of both of these devices. When a glove is used, a ball striking it can be much more firmly and surely held than would be possible if the player wore a mitt; and on the other hand, the fingers of the glove being 25 separated the leather is very frequently split where the fingers join the palm owing to the hard impact of the ball thereagainst. Furthermore, with a hand covering in the form of a mitt possessing the requisite flexibility in the finger portion, a player is less likely to fail of catching a ball than where 30 a glove construction is used, owing to the fact that a ball is more completely pocketed in a mitt than in a glove, but a mitt, as at present generally constructed, is not flexible enough to permit the fingers to freely 35 close over a ball, the finger portions of a mitt being sewed along their edges to the back of the mitt to provide separate but not 40 separated or separable finger portions.

The object of the present invention is to provide a hand covering having all of the characteristics of flexibility found in a glove, together with the command of the 45 finger portion thereof, and at the same time embodying the more desirable characteristics of a mitt.

The structure hereinafter described embodying practically a glove structure in- 50 cased in a mitt-covering, permits the use of a glove construction which is much cheaper to make than an ordinary "fielder's" glove inasmuch as the glove proper consisting of the fingers and the palm portion need not 55 be of as high a grade of leather as in a glove

which is to receive the direct impact of the ball, and all of the padding is secured to the outside of the glove structure instead of inside, as in "fielders'" gloves, the incasing of this glove structure within a mitt 60 covering serving to protect all of the glove construction. If this were not so and any part of the glove construction were visible it would be necessary to provide as good an exterior appearance to the glove structure as though it were to be used as an ordinary fielder's glove, which would entail an additional expense. 65

The invention is fully set forth in the following specification and illustrated in the 70 drawings accompanying the same, in which,—

Figure 1 is a rear elevation of the leather covering for a mitt as usually constructed. Fig. 2 is a like view of a glove inserted 75 within this mitt covering shown in Fig. 1, a part of the latter being broken away to show the location of the glove fingers, the exposed portion of the latter being in section. Fig. 3 is a cross sectional view taken on 80 line 3—3 of Fig. 1. Fig. 4 is a cross sectional view on line 4—4 of Fig. 2. Fig. 5 is a front elevation of a glove showing the padding stitched to the fingers and the palm thereof, auxiliary padding being shown applied thereto at the base of the palm. Fig. 6 is a sectional view on line 6—6, Fig. 5, showing the padding secured to one of the 85 fingers of the glove. Fig. 7 is a sectional view on line 7—7, Fig. 8, showing auxiliary 90 padding for the finger portion of the glove. Fig. 8 is a front elevation of a glove having the usual surface padding and auxiliary padding extending across the base of the palm, as in Fig. 5, and continued up one 95 side and across the finger tips.

Referring to the drawings, Fig. 1 shows the bag-like covering ordinarily used in the manufacture of a mitt, this being indicated as a whole by *a* in the various figures of 100 the drawing.

Fig. 5 shows a glove structure in front elevation which is inserted in the mitt covering shown in Fig. 1. The glove structure is inserted in the mitt covering and stitched 105 thereto as follows: First, the tips of the fingers *b* of the glove are spread apart, the width of the mitt covering permitting this, these tips being stitched to the edge of the mitt, as at *c* Fig. 2. The glove and mitt 110

are then stitched together around the wrist, as at *d*, and around the border *g* of the opening *h* in the back of the mitt when the glove is finished. By stitching the glove fingers 5 at the tips thereof to the inner edge of the mitt covering with the fingers spread apart, it permits lateral movement of all of the fingers within the limits of the mitt, practically the same as though the fingers were 10 not stitched to the mitt at all, it being of course understood that the material of which the mitt covering is made is flexible enough to permit this lateral movement of the fingers. In other words, by thus securing 15 the glove in the mitt member, the fingers of the glove may be readily closed over a ball or moved laterally, that is, spread apart to provide for an efficient grasping or holding of the ball, the edge of the mitt 20 being flexible and permitting these different movements of the fingers of the glove member.

Referring to Fig. 5 again, the dotted line *e* indicates the outline of the leather glove which is made in the usual manner, 25 the padding *f* for the finger portions and palm thereof being stitched to the edges of the glove and fingers. The outline of this padding is shown in full lines and in section 30 in Figs. 4, 6, and 7. When the glove construction shown in Fig. 5 is inserted within the mitt covering shown in Fig. 1 and secured thereto in the manner described, the article has substantially all of the flexibility 35 of the glove, and the leather covering of the mitt and the padding *f* protects the glove against ripping or splitting in the palm; this flexibility of this structure is due to the fact that the fingers and thumb 40 of the glove are not restricted in their movement laterally owing to the flexible nature of the mitt covering *a* within which the glove structure is inclosed, and because the finger-tips are separated before being 45 cured to the covering, they are free to move laterally and are not drawn down into the covering when the fingers are closed over

the ball. A closer approximation to the mitt may be attained by applying to the base of the palm, as shown in Fig. 5, an 50 auxiliary padding *h* which is stitched to the glove padding *f* before the glove is inserted within the mitt covering. If it is desired to provide a structure which shall have all 55 of the characteristics of the mitt, together with much greater flexibility than is possible with mitts as generally constructed at present, this auxiliary padding *h* may be extended up the outer edge of the glove along the little finger and then across the 60 finger-tips, as shown in Fig. 8, thereby producing a deeper pocket in the palm, but without interfering with the free movement 65 of the fingers to an appreciable degree. The great flexibility of the structure herein described provides a hand covering which may be used by a "fielder" and which has all of the desirable characteristics of the mitt as at present constructed and which will, at the same time, provide a catcher with a 70 hand covering having all the desirable characteristics of the fielder's glove. The thumb and the edge of the mitt-covering may be united by the flexible web *m*, if desired, or any of the well known equivalents of this 75 web may be used.

What I claim, is:—

1. A hand covering comprising a fingered padded glove member and an inclosing casing therefor of flexible material, the fingers 80 of the glove member being secured to the casing only at the tips of the fingers with the wrist portion of the gloved member secured to the wrist portion of the casing.
2. A hand-covering comprising a fingered glove member and an inclosing casing therefor of flexible material, the glove member being secured at its extremities only to said casing. 85
